UNITED STATES PATENT OFFICE.

GUSTAV THALER, OF OAKLAND, CALIFORNIA.

FRUIT-JAR CLOSURE.

1,178,969.

Specification of Letters Patent. Patented Apr. 11, 1916.

Application filed January 31, 1914, Serial No. 815,608. Renewed December 27, 1915. Serial No. 68,921.

To all whom it may concern:

Be it known that I, GUSTAV THALER, a citizen of the United States, residing at Oakland, in the county of Alameda and State of California, have invented certain new and useful Improvements in Fruit-Jar Closures, of which the following is a specification.

This invention relates to improvements in fruit jar closures, which may be adapted to any of the ordinary type of jars.

The principal object of my invention is to provide a seal which is easily applied and removed.

A second object of my invention is to provide a non-metallic closure and so prevent corrosion by contact with the fruit acids.

A further object is to provide a cheap and sanitary cover, which will be used but once and then discarded.

With these and other objects in view my invention consists in the novel arrangement and combination of parts as herein described and pointed out in the appended claims.

For a full comprehension of the invention reference should be had to the drawing forming a part of the specification wherein,

Figure 1 is a vertical section of a jar with a screw cap and having my device applied thereto. Fig. 2 is a top plan view with the screw cap removed. Fig. 3 is a fragmentary vertical sectional view showing the jar top sealed and the applying device removed.

Denoting corresponding parts by the same numerals, 1, is the jar body having the neck portion 2, and in the form here shown screw threads 3 are provided on the outside of the neck engaging a cap 4. While this cap is shown in threaded engagement with the jar neck it will be understood that any other means of securing it thereto, which will resist an upward pull will suffice, as the securing of this top in no way affects the sealing of the jar.

To effect the sealing of the jar I provide a gasket 7 having the circular center disk 8, around the periphery of which is formed the upstanding wall 9, and which fits snugly within the neck 2. At the top is a laterally extending rim 10 adapted to rest on top of neck 2. This gasket 7 may be of any suitable material, but in practice I use a stiff paper heavily coated with a wax like substance, especially on the side adjacent the

glass. Between this gasket and the cap 4 I provide a compression member 11 formed with the central conical portion 12, the upstanding annular flange 13 adapted to fit within the wall 9 of the gasket, and the lateral rim 14 resting on the rim 10 of the gasket.

The cap 4 is provided with a screw threaded hole in alignment with the apex of the conical disk 12. Through this hole is threaded a screw 16 having a head 17 by which it may be readily turned. Extending from the center of this disk is a radial slot 15 through the conical center 12 the upstanding flange 13 and the lateral rim 14. Thus when pressure is applied to the apex of the conical portion the tendency is to open the cone and press the flange 13 outwardly.

In use, after placing the articles to be preserved within the jar the gasket 8 is applied with the rim 10 resting on the top of the neck 2. The compression member 11 is then placed over the gasket and the cap 4 fastened to the jar, in this case by screwing it thereon. Screw 16 is next turned to bring the point thereof into contact with the apex of disk 12, thus pressing the latter downward and at the same time expanding the flange 13 against the wall 9 and the latter against the inner surface of the neck. At the same time the rim 14 presses the rim 10 into intimate contact with the top of the neck and the heat of the contents melts the wax-like substance and firmly holds the gasket to the glass, this action being also assisted by the vacuum within the jar. When the contents cool the cap 4 and compression member 11 may be removed leaving the jar sealed as shown in Fig. 3, and to open it is only necessary to cut out the disk 8 with a knife or other sharp instrument. Thus it will be seen I have provided an effective device for the purpose mentioned and while I have shown the preferred embodiment of my invention I wish to include all such modifications and changes in form and detail as properly fall within the scope of the annexed claims.

What I claim and wish to cover by Letters Patent is:—

1. A container comprising a body, a cap, a compressible gasket therebetween covering the entire mouth of said container, a convex disk between said cap and said gasket, a slit in said disk to allow the lateral expansion

of the edges thereof, and screw means in said cap to flatten said disk and force the edges down and outwardly.

2. A container comprising a body, a cap, and a gasket therebetween, a convex disk between said gasket and said cap, said disk having an annular flange, a lateral rim, a radial slit, screw means carried by said cap adapted to press against said convex disk thereby.

squeezing the said gasket between said flange and the inner wall of said neck and between said rim and top edge of said neck.

In testimony whereof I affix my signature in presence of two witnesses.

GUSTAV THALER.
